BRUSH OF THE PUSH BROOM TYPE

Alfred L. Le Febvre, Windsor, Conn., assignor to
 The Fuller Brush Company, Hartford, Conn., a
 corporation of Connecticut

Application December 7, 1946, Serial No. 714,681

8 Claims. (Cl. 15—144)

1

The invention relates more particularly to the handle construction of a brush, and while the invention is not necessarily so limited, it is particularly adapted for use in a brush of the push broom type.

One object of the invention is to provide a brush of the push broom type having a pivoted handle and having improved means operable by rotation of the handle for locking the handle in any one of a plurality of positions of pivotal adjustment with respect to the base.

Another object of the invention is to provide a brush of the push broom type having a handle pivoted thereto and having a brace pivoted for relative movement with the handle and serving to prevent deflections of the handle in the direction of its pivotal axis.

Still another object of the invention is to provide a brush having a wooden handle and having improved means for securing the handle in place.

Other objects of the invention will be apparent from the drawings and from the following specification and claims.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings:

Fig. 1 is a side view of a brush embodying the invention.

Fig. 2 is a transverse vertical sectional view taken along the line 2—2 of Fig. 1.

Fig. 3 is a longitudinal vertical sectional view taken along the line 3—3 of Fig. 2.

Fig. 4 is a view of the blank for forming the ferrule which holds the wooden handle.

Fig. 5 is a side view of the ferrule as it appears prior to its assembly with the handle.

Fig. 6 is a plan view of the ferrule as shown in Fig. 5.

Fig. 7 is a horizontal sectional view taken along the line 7—7 of Fig. 5 but showing the ferrule engaged with the wooden handle.

Referring to the drawings, particularly Figs. 1 to 3 thereof, 10 is the base of the brush which is normally horizontal. Secured to the base 10 and projecting downwardly therefrom are suitable bristles. While the present invention is not so limited, the base 10 and the means for securing the bristles thereto may be in accordance with

2

the disclosure in my copending application for Brush, Serial No. 675,236, filed June 7, 1946, of which this present application is a continuation-in-part. Reference is made to the said copending application for any details not herein fully disclosed.

The base 10 comprises a single piece of extruded material, ordinarily metal, the base being of uniform cross section throughout. The base 10 may be varied in length as required. The base 10 is provided, preferably immediately adjacent its sides, with two longitudinal open-bottom grooves 12, 12 which are open at their ends. The grooves are narrowest adjacent their open bottoms and the side walls of the grooves converge downwardly toward the said narrowest portions. As shown, the grooves 12, 12 are formed between downward extending longitudinal flanges 14, 14 and 16, 16. The inner face of each flange 14 is vertical and the outer face of each flange 16 is inclined.

Preferably, for a purpose to be presently stated, the inner faces of the flanges 16, 16 which face toward the center are inclined so as to converge downwardly. To conserve material the bottom edges of the flanges 16, 16 may be provided with longitudinal grooves 18, 18.

The base 10 is preferably provided at the center with a longitudinal open-bottom groove 20 which is open at its ends. The groove is narrowest adjacent its open bottom and the side walls of the groove converge downwardly toward the said narrowest portion. As shown, the groove 20 is formed between downward extending longitudinal flanges 22, 22, the inner faces of which converge downwardly.

The brush includes a plurality of brush strips, portions of which are engaged with the grooves 12, 12 and with the groove 20 when such groove is provided. Each brush strip comprises a metallic member 24 which constitutes the holder for the bristles 26 of the strip, the said member being bent so that it is U-shaped in cross section and constitutes a channel, the bristles 26 being doubled within the U-shaped holder or channel member and being held by the walls of the member and by a central core wire 28. In the manufacture of the brush the required brush strips are cut to length from previously formed longer strips. It will be understood that the term "bristles" as herein used is intended to be generic and to include bristles or fibers of any kind suitable for use in brush manufacture.

Entered endwise in the grooves 12, 12 are brush strip portions 30 and 32, the holders 24 of the

said strip portions engaging the converging side walls of the grooves above the narrow bottoms thereof so that the brush strips are firmly held against relative downward movement. The sizes of the holders 24 and of the grooves are so related that considerable force is required for the endwise insertion of the holders in the grooves. The resultant friction is sufficient to prevent any accidental or unintended removal of the holders from the grooves. Preferably the two strip portions 30 and 32 are connected by means of an integral end portion (not shown). Preferably strip portions such as 30 and 32, together with their connecting end portions, are inserted in the grooves 12, 12 in the base from both ends thereof.

In order that there may be a larger body of bristles at the ends of the brush I preferably provide at each end a supplemental brush strip which is bent to provide a connecting end portion (not shown) and two parallel portions 40, 40. The spacing between the two brush strip portions 40, 40 is such that the holders of the said portions can be firmly engaged with the downwardly converging faces of the flanges 16, 16, as shown in Fig. 2.

When a central groove such as 20 is provided, brush strip portions are inserted therein in the manner already described in connection with the brush strip portions 30 and 32. Preferably there are two brush strip portions 42, 42 which are inserted in the groove 20 from opposite ends thereof.

In order to cover the ends of the base and the parts of the brush strips which project beyond the said ends, two end caps 44, 44 are provided. The details of these end caps are fully set forth in the said copending application and need not be here described as they do not constitute a part of the present invention.

The base 10 is preferably provided with a central transverse slot 46 which is open at the top and which communicates with the groove 20. The walls of the groove 20 are cut away at the said groove. A handle holding member 48 extends through the slot 46 and portions of the said member are seated in the groove 20 between the inner ends of the brush strips 42, 42 in the said groove. Preferably, the portions of the member 48 which are seated in the groove are pivot elements 50, 50 which enable the member 48 to move pivotally in the slot 46 about the longitudinal pivotal axis of the said elements. A handle 52 is provided, preferably formed of wood, this being connected with the handle holding member 48. Preferably and as shown, the handle holding member 48 is threaded at its upper end and the handle is provided with a threaded bottom member 54 at its lower end which receives the threaded upper portion of the member 48. Carried by the base 10 is a bracket 56 which may be secured to the base by spot welding. The bracket 56 has an arcuate or convex face 58 which is concentric with the axis of the pivot elements 50, 50, and it has a slot 60 through which the member 48 extends, the said slot being in register with the slot 46 in the base. When the handle is loosely engaged, it can be adjusted to any relative angular position within the limits of the slot 60, and by then turning the handle about its own axis the threaded engagement of the member 54 with the member 48 forces the said member 54 into clamping engagement with the convex face 58 of the bracket to lock the handle in its adjusted position.

Preferably the convex upper face 58 of the bracket 56 of the base 10. The plate 80 has a transverse

bracket 56 is not only curved transversely to be concentric with the horizontal longitudinal axis of the pivot elements 50, 50 but it is also curved longitudinally to be concentric with a horizontal transverse axis intersecting the aforesaid longitudinal axis. When the face 58 is so curved it is in fact a portion of a sphere. The bottom face of the bottom member 54 is similarly curved and is in fact a portion of a sphere. The provision of the said mating spherical faces provides a surface contact between them which is in contrast with the line contact which would be provided if the face 58 were curved only transversely and if the bottom face of the member 54 were flat.

The bottom member 54 of the handle 52 is secured to the handle by means of a ferrule 62, the details of which are shown in Figs. 4 to 7. For forming the ferrule 62 a sheet metal blank 64 is provided, as shown in Fig. 4. Slots 66, 66 are provided at the ends of the blank which divide it into upper and lower portions. The ends of the upper portion are notched at 68, 68 to provide teeth 70, 70. The blank 64 is bent to a generally cylindrical shape, as shown in Figs. 5 and 6. The lower portion of the blank forms a complete cylinder with the ends abutting, as shown, but the upper portion forms only an incomplete cylinder with the end portions extending tangentially as shown in Fig. 6. The teeth 70, 70 are bent inward at right angles to the tangential portions as shown.

The cylindrical lower portion of the blank is of such diameter as to receive and fit the bottom member 54 and this member is inserted and secured in place by welding, as indicated. The diameter of the partly cylindrical upper portion, as shown in Fig. 6, is such as to fit the bottom portion of the wooden handle 52. After the bottom member 54 has been welded in place the handle is inserted and then the tangential portions of the ferrule, as shown in Fig. 6, are bent inward to conform to the curvature of the handle, the teeth 70 being forced into the handle as indicated in Fig. 7. It will be seen that the teeth 70, by reason of being imbedded in the handle, serve to securely connect the handle with the ferrule thus positively preventing removal thereof. The bottom member 54 serves not only as a means of connection with the handle holding member 48, as already described, but it also serves to prevent the ferrule from opening to release the handle. It will be seen that, if the member 54 were not provided and welded in place as shown, there would be a tendency for the ferrule to open up during use and for the teeth 70, 70 to gradually work out from their imbedded positions. Any such opening of the ferrule is definitely prevented by reason of the fact that it is welded to the member 54.

Preferably a brace 72 is provided which engages the handle and serves to reinforce the hinge connection at 50, 50. As shown, the brace 72 is a single piece of heavy wire which is bent to form a loop 74 embracing the handle at a position substantially above the hinge connection at 50, 50 and substantially above the bracket 56. This loop permits the handle to be turned in the manner already described for clamping and unclamping. The ends of the brace 72 extend diagonally downwardly and outwardly and are then bent to form horizontal trunnions 76, 76. These trunnions are entered in apertures formed in ears 78, 78 bent upwardly from a plate 80 secured by spot welding or otherwise to the top 70 of the base 10. The plate 80 has a transverse

slot which registers with the transverse slot 46 in the base, and the arched portion of the bracket 56 extends over the plate 80. The plate extends longitudinally at both sides of the bracket, the said ears 78, 78 being at the ends of the plate. The axis of the trunnions 76, 76 is somewhat above the axis of the handle at 50, 50 but the loop 74 can move slightly vertically on the handle to compensate for this lack of alignment of the two axes.

It will be seen that the brace 72 moves pivotally with the handle when the handle is adjusted and it serves to reenforce the hinge connection at 50, 50 and to prevent any longitudinal deflection of the handle relatively to the brace.

The invention claimed is:

1. In a brush of the push broom type, the combination of a normally horizontal brush base having a transverse slot therein, bristles secured to the base and extending downward therefrom, a bracket secured to the base at the top thereof and having a convex upper face which is concentric with a longitudinal horizontal axis located below the slotted portion of the base and which is also concentric with a transverse axis intersecting the said longitudinal axis, the said bracket also having a transverse slot therein which is in register with the said slot in the base, a handle holding member extending through both of the said slots and pivoted at its lower end to the base independently of the bracket for movement about the aforesaid horizontal axis, the upper end portion of the said member being threaded and being movable through the slot in the bracket, and a handle having a lower end element provided with a concave bottom face shaped to fit the convex upper face of the bracket and provided with a longitudinal threaded hole for receiving the threaded upper end portion of the holding member, the said lower end element of the handle being engageable with the convex face of the bracket and being adapted to be clamped thereto or released therefrom upon rotation of the handle relatively to the holding member.

2. In a brush of the push broom type, the combination of a normally horizontal brush base, bristles secured to the base and extending downward therefrom, a handle, a hinge connection between the lower end of the handle and the base permitting relative movement of the handle about a longitudinal axis, a handle brace comprising a single wire formed at the center with a loop surrounding the handle substantially above the hinge connection, the said loop permitting relative movement of the brace longitudinally of the handle, means for hinging the ends of the brace to the base for movement with the handle about a longitudinal axis above the first said axis, the last said means enabling the brace to reenforce the hinge connection for the handle and prevent longitudinal deflection of the handle relatively to the base, and means independent of the bracket serving upon rotation of the handle about its own axis to lock the handle in any one of a plurality of positions with respect to the base.

3. In a brush of the push broom type, the combination of a normally horizontal brush base, bristles secured to the base and extending downward therefrom, a bracket secured to the base at the top thereof and having a convex upper face which is concentric with a longitudinal axis and also having a transverse slot therein, a handle holding member threaded at its upper end

and pivoted at its lower end to the base independently of the bracket for movement about the aforesaid longitudinal axis, the threaded upper end portion of the said member extending through the slot in the bracket and being movable therein, a handle having a lower end element having a longitudinal threaded hole for receiving the threaded upper end portion of the holding member, the said lower end element of the handle being engageable with the convex face of the bracket and being adapted to be clamped thereto or released therefrom upon rotation of the handle relatively to the holding member, and a handle brace pivoted to the base independently of the handle holding member for movement about a longitudinal axis, the said brace engaging the handle substantially above the bracket and in a manner permitting rotation of the handle and the said brace serving to prevent longitudinal deflection of the handle relatively to the base.

4. In a brush of the push broom type, the combination of a normally horizontal brush base, bristles secured to the base and extending downward therefrom, a bracket secured to the base at the top thereof and having a convex upper face which is concentric with a longitudinal axis and also having a transverse slot therein, a handle holding member threaded at its upper end and pivoted at its lower end to the base independently of the bracket for movement about the aforesaid longitudinal axis, the threaded upper end portion of the said member extending through the slot in the bracket and being movable therein, a round handle having a lower end element having a longitudinal threaded hole for receiving the threaded upper end portion of the holding member, the said lower end element of the handle being engageable with the convex face of the bracket and being adapted to be clamped thereto or released therefrom upon rotation of the handle relatively to the holding member, and a handle brace comprising a single wire formed at the center with a loop surrounding the handle substantially above the bracket, and means for hinging the ends of the brace to the base for movement with the handle about a longitudinal axis, the last said means enabling the brace to prevent longitudinal deflection of the handle relatively to the base.

5. In a brush of the push broom type, the combination of a normally horizontal brush base having a transverse slot therein, bristles secured to the base and extending downward therefrom, an arched bracket secured to the base at the top thereof and having a convex upper face which is concentric with a longitudinal horizontal axis located below the slotted portion of the base, the said bracket also having a transverse slot therein which is in register with the said slot in the base, a handle holding member extending through both of the said slots and pivoted at its lower end to the base independently of the bracket for movement about the aforesaid horizontal axis, the upper end portion of the said member being movable through the slot in the bracket, a movable handle connected with the handle holding member, a plate secured to the top of the base within the arched portion of the bracket and extending longitudinally at both sides of the bracket, the said plate having a transverse slot in register with the slot in the base, and a handle brace pivoted to the said base near the ends thereof and at opposite sides of the bracket, the said brace engaging the handle substantially above

the bracket and serving to prevent longitudinal deflection of the handle relatively to the base.

6. The combination in a brush, of a brush base, bristles secured to the base and projecting therefrom, a handle holding member connected with the base and threaded at its upper end, a wooden handle, a ferrule comprising a strip of metal bent to surround the lower end portion of the handle and having teeth at its end portions which are bent inward and embedded in the handle, and a metallic member at the bottom of the handle welded to the lower end of the ferrule and serving to prevent the ferrule from opening to release the handle, the last said member having a central threaded aperture for receiving the threaded portion of the holding member.

7. The combination in a brush, of a brush base, bristles secured to the base and projecting therefrom; a handle holding member connected with the base and threaded at its upper end, a wooden handle, a ferrule comprising a strip of metal bent to surround the lower end portion of the handle and having teeth at its end portions which are bent inward and embedded in the handle, the said ferrule being so positioned as to project below the said lower end portion of the handle, and a metallic member

15 at the bottom of the handle fitting within and welded to the projecting lower end of the ferrule and serving to prevent the ferrule from opening to release the handle, the last said member having a central threaded aperture for receiving the threaded portion of the holding member.

8. The combination in a brush as set forth in claim 7, wherein the strip constituting the ferrule has an upper portion the ends of which are bent 20 inward and embedded in the handle and has a lower portion the ends of which abut to form a complete enclosure for the threaded metallic element.
